AUTOMATIC RADIO TUNER

Albert S. Wells, Chicago, Ill., assignor to Wells-Gardner & Co., Chicago, Ill., a corporation of Illinois

Application January 14, 1943, Serial No. 472,371

30 Claims. (Cl. 250—20)

The tuning device of the present invention is designed primarily for use in situations where it is desirable to pick up reports or signals in recurrent sequence from a group of stations transmitted in different frequencies; and in order to successively bring in these stations, provision is made for automatically adjusting the plates of the condenser in each case, and for a predetermined interval, to the required position to bring in the stations in sequential order.

Although the present invention is designed primarily with reference to the automatic operation above described, provision is made for disconnecting the automatic train in order to permit manual adjustment in the usual manner. With the above ends in view, the mechanism is so designed that continuously motor driven means may be successively and sequentially brought into train with the devices which regulate the degree of adjustment of the condenser plates so that in each instance, a regulating movement, at the proper time, and in the required degree will be imparted to the rock shaft which carries the group of condenser plates with the result that for a timed interval the parts will be adjusted to the degree required to attune the apparatus to the frequency of each of the sending stations comprising the group.

Further objects and details will appear from a description of the invention in conjunction with the accompanying drawings, wherein—

Figure 1 is an exterior perspective view of the tuning apparatus of the present invention;

Fig. 2 is a diagram of the wiring circuits employed;

Fig. 3 is a sectional view through the casing at a point near the right-hand end thereof as viewed in Fig. 1;

Fig. 4 is a similar view taken through the center of the casing;

Fig. 5 is a plan view of the operating mechanism with the casing broken away to reveal the interior;

Figures 6, 7, and 8 are views of the shuttle bar, thrust bar, and adjustable trip mechanism for regulating the throw of the condenser plate rock shaft, showing the parts in successive stages of the operation;

Figures 9 and 10 are perspective views of the vertically movable armature bars which are actuated in sequence to control the setting of the thrust bars;

Fig. 11 is a perspective view of the universal rocking plate for selectively engaging and releasing the armature bars;

Fig. 12 is a composite perspective view of the adjusting block for switching the apparatus from automatic to manual operation; and

Fig. 13 is a perspective view of the latching switch.

The automatic apparatus, as a whole, is housed within a casing comprising a rear wall 10, end walls 11 and 12; a front wall 13, which merges into an oblique panel 14, and a top wall or roof 15. Within the casing is located a base plate 16 which supports a frame box of rectangular formation comprising end walls 17 and 18, a front wall 19, and a rear wall 20. The frame box is provided along its base with a flange 21 which is rigidly secured to the base plate 16. The inner frame box affords a support or framework for most of the mechanism presently to be described.

The casing stands in adjacent relation to a condenser 22 comprising a set of condenser plates 23 mounted upon a divided shaft 24 which extends through the casing from end to end thereof, and terminates in a knob 25 provided to permit direct operation in lieu of either the automatic or button control.

The rock shaft, within the frame box, carries a pair of arms 26 which support the ends of a universal swinging bar 27 adapted to be contacted by any one of a series of lugs 28 each carried by a thrust bar 29 normally held in retracted position by a spring 30. Each of the thrust bars is intended to attune the condenser to the frequency of a particular sending station, and the range of movement of each thrust bar will be correspondingly limited by means presently to be described to the tuning requirements of the associated station. The thrust bars are thus in the nature of movement-transmitting elements adapted to variably rotate the rocking shaft to meet individual tuning requirements.

Each thrust bar is provided on its upper edge with a rearwardly pointing finger 31 which overlies a notch or recess 32 open at its rear end to afford clearance for the reciprocation of a constantly operating movement-imparting element 33 in the nature of a shuttle bar 33 which is carried at each end by a plate 34 which lies in sliding abutment against the inner face of the adjacent end wall of the frame box. Each shuttle bar plate is supported and guided by a headed guide stud 35 and a crank stud 36, both of which extend through an adjacent slot 37 in the end wall of the frame box. (See Fig. 3).

The crank studs at opposite ends of the shuttle bar each provide a mounting for a link 38 having its forward end pivoted to a disc 39 on

a shaft 40 which extends through the end walls of the frame box. Immediately above is a transmission shaft 41 provided with a spur pinion 42 which meshes with a spur pinion 43 on the shaft 40 and serves to impart continuous rotation thereto. The transmission shaft is reduced at its right-hand end 44 which carries a beveled pinion 45 meshing with a drive pinion 46 on a rearwardly extending shaft 47, carrying at its rear end a beveled pinion 48 meshing with a drive pinion 49 on a vertical shaft 50 in train with reduction gear mechanism 51 driven by the shaft 52 of a constant speed motor 53 supported upon the base plate 16 near the rear right-hand end of the casing. (See Fig. 3.)

Referring now particularly to Figure 4 in its relation to Figures 6, 7, and 8, it will be noted that in Fig. 4 the thrust bar there illustrated is tilted upwardly at the rear end so that the shuttle bar 33 during its constant lateral reciprocations will clear the finger 31 and enter the notch 32, which operation is ineffective to impart movement to the thrust bar. In Fig. 6 the thrust bar has been lowered slightly so that the end of the finger 31 lies in the path of movement of the shuttle bar 33 which, however, is here shown in its rearward or retracted position. Fig. 7 shows the shuttle bar advancing to carry forward the thrust bar and with it the lug 28 which engages the universal swinging bar 27 which in Fig. 7 has been moved forwardly to rock the condenser shaft 24. It will be noted from Fig. 7, however, that the thrust bar still stands in position to engage the shuttle bar which is continuing its advance, which range of movement of the shuttle bar must be the maximum required to attune the condenser plates to each of the sending stations of the group.

It is therefore necessary, in each instance, that the thrust bar shall maintain contact with the advancing shuttle bar only during the period required to impart the intended rocking movement to the condenser shaft and shall thereupon be disengaged therefrom by mechanism now to be described.

Each of the thrust bars has associated therewith an underlying latch bar 54 provided in its upper edge with a notch 55 having an abrupt rear face 56 which coacts with a rider lug 57 on the associated thrust bar which lug has an abrupt rear face 58 and a beveled forward face 59 in complementary relation to a beveled forward face 60 of the associated notch.

Near the rear end each latch bar is provided with a guide slot 61 through which is entered a universal supporting rod 62 adapted to sustain the rear ends of the entire group of latch rods each of which is individually adjustable by means of a screw 63 threaded through an ear 64 laterally extending from the latch bar. The respective adjusting screws are carried by a bank of spindles 65 which extend through the forward wall of the frame box and through the front wall 13 of the casing and terminate in a row of adjusting knobs 66, each of which is intended to secure proper attunement with a particular sending station.

Each spindle immediately in advance of the threaded stem carries a washer 67 backed by a spring clip 68 bearing against the wall of the frame box. By rotating the individual knobs 66, the latch bars can be individually adjusted to bring the respective notch shoulders 56 each to the proper position to clear the associated thrust

bar at the proper instant to break contact with the advancing shuttle bar.

Up to this point the rider lug 57 has been riding forwardly upon the edge of the associated latch bar and under the thrust of the shuttle bar, but as soon as the rear edge of the rider lug registers with the rear edge of the notch, the thrust bar, under spring tension, will drop down into the position shown in Fig. 8, thereby causing the finger 31 to release from contact with the shuttle bar so that the latter will thereupon continue to the limit of its advance without imparting additional movement to the thrust bar.

Since the effective movement of the thrust bar determines the degree to which the condenser shaft will be rocked, the proper amount of movement for each sending frequency can be regulated by the individual adjustments imparted to the respective knobs 66 comprising the group.

The rear or tail end of each of the thrust bars is normally held elevated as in Figure 4 by contact with the shoulder 69 forming the lower terminus of a lateral recess 70 in an associated releasing device which in the present instance is in the form of an armature bar 71 (or 71a as the case may be), which armature bars are equal in number to the number of thrust bars, but in order to compactly arrange the mechanism, the armature bars of the type shown in Figure 9 are alternated with the type shown in Figure 10.

Each armature bar consists of a section 72 (or 72a) formed of magnetic material, a metal section 73 (or 73a) formed of non-magnetic material, and a tail piece 74 provided with an inwardly projecting foot 75. The armature bar of Fig. 10 also provides an upper extension guide bar 76 which is simply for the purpose of adding the required length. Aside from the slight difference in detail, the operation of each armature bar comprising the entire group is the same, and the armature bars need not be of the specific form illustrated.

Each of the armature bars has its magnetic section 72 mounted as the pole piece within a solenoid coil 77 carried within a frame 78 secured to the rear wall of the frame box and so arranged that when the coil is energized, the armature bar will be drawn downwardly against the tension of a coil spring 79 bearing against a cap 80 thereby lowering the shoulder 69 and permitting the rider lug on the associated thrust bar to make contact with the underlying latch bar which brings the finger 31 into the path of travel of the shuttle bar so that the thrust bar will be advanced to the required extent upon the next forward reciprocation of the shuttle bar.

The armature bar, however, will be drawn down still farther until the foot engages the lower edge of a universal swinging latch plate 81 (Figures 4 and 11) which is carried by a trunnion rod 82 having its ends journaled within the end walls of the frame box, which trunnion rod is provided with upstanding fingers 83 engaged by springs 84 which normally hold the latch plate in rearwardly retracted position but permit it to be swung forwardly by contact with the foot of an armature bar until the latter engages the lower edge and thus remains latched until the universal latch bar again is swung forwardly by the descent of another armature bar which releases the engagement of the first bar.

In the case of the alternate armature bars 71a, each bar is arranged to carry its magnetic section 71a through a solenoid coil 77a carried by a frame 78a located at a lower level so that by thus

staggering the armature bars of the two different forms, an upper and a lower row of solenoid coils may be employed thus greatly reducing the spacing required for the coils and the frames supporting the same. Each of the armature bars 71a acts against the tension of a spring 85 corresponding in function to the springs 79. (See Fig. 10.)

In order to successively energize the respective solenoids at timed intervals which, however, need not be uniform, the following mechanism is employed.

Each of the solenoids is in circuit with an assigned pair of spring switch members 86 and 87 (Fig. 4) which are normally open and the lower switch member is associated with a spring arm 88 carrying a roller 89 adapted to be contacted by a boss 90 on the surface of a constantly rotating timing drum 91 carried by a shaft 92, which constitutes a timing device for selectively and successively energizing the individual solenoids.

The respective bosses are arranged in a spiral row, as shown in Fig. 5, so that each of the switches will be closed by one only of the entire series of bosses during a single rotation of the drum.

The shaft 92 at its right-hand end carries a worm wheel 93 meshing with a worm 94 carried by a worm shaft 95 mounting a spur gear 96 in mesh with a driving spur gear 97 on the shaft 47 so that power derived from the motor will rotate the drum at a relatively slow but uniform rate of speed, thereby in turn bringing the respective bosses 90 into contact with the switch rollers 89 associated therewith so that the switches in turn will be momentarily closed thereby energizing the associated solenoids which draw down the respective armature bars into position to be latched by the universal latch bar 81. The closing of each switch is but momentary but thereafter the latch bar will function to hold the armature bar in lowered position during a predetermined interval of time and until the next boss of the series makes engagement with the associated switch roller which results in the release of a previously latched armature bar and results in a latching of the second bar.

It is also possible to disable the automatic lowering of the armature bars by the rotation of the timing drum, and to effect a selective lowering of any one of the armature bars by means of the depression of any one of a series of aligned finger button switches 98 located on the face of the panel 14 immediately below a corresponding row of light bulbs 99. The circuit wire which permits this operation is shown in Fig. 2 and will be presently described in detail.

The above may be termed a semi-automatic operation, but it is also possible to operate the condenser directly by the rotation of the knob 25 at the right-hand end of the casing. This capacity for hand operation is desirable in preliminarily adjusting the positions of the individual trip bars by the turning of the knobs 66 so that it is possible to hand adjust the condenser for any particular station until clear reception follows after which the latch bar can be adjusted to a corresponding position.

In changing from hand operation to automatic operation a push rod 100 is employed, which is entered through guide lugs 101, 102, 103 on the outer face of the frame box wall 17. The push rod carries a collar 104 provided with a bent finger 105 which engages the lower end of a coil spring 106, the upper end of which is secured to a bent finger 107 extending obliquely upward from

the shaft 24. When the rod 100 is turned to the position shown in Fig. 3, the finger 105 will occupy its lowermost position, thereby tensioning the spring 106; but when the shaft is half-turned to bring the finger 107 to the position indicated in dotted lines, the tension on the spring will be released so that it will be ineffective to rotate the rock shaft 24.

As shown in Fig. 12, the collar 104 is provided in its inner face with a cross notch 108 which is adapted to receive a spline 109 on the face of a flanged lug 110 secured to the end wall of the frame box. The inner end of the push rod 100 is adapted to engage a finger 111 on the trunnion shaft 82 so that as the rod is pushed inwardly, the trunnion shaft will be rocked and the universal plate 81 will release and clear any one of the armature bars which may stand in depressed position. The turning of the push rod to the spring releasing position and the locking of the rod by the engagement of the notch 108 with the spline 109 under the thrust of a spring 112 and the turning of a switch 113 will condition the machine for the semi-automatic operation to be controlled by the depression of the buttons 98 in any desired or timed sequence.

In order to operate the mechanism satisfactorily it is necessary to mute the loud speaker momentarily during the interval required to shift from one station to the next in order to cut out disturbing mechanical or electrical noises and to again bring in the loud speaker after tuning has been effected; and it is also necessary to make provision for shifting the illumination from one light to the next to register with the station next to be attuned. It is also desirable to deenergize the currently operating solenoid after attuning has been effected to prevent overheating during the interval of reception after the necessary tuning adjustment has been secured by the mechanism heretofore described. Provision must also be made for shifting from automatic to button control while at the same time making provision for the continued utilization of all portions of the mechanism which control the tuning to the particular stations in response to the selective control by the buttons rather than by the continuously rotating drum and the electrical means provided for attaining these various results are illustrated in the wiring diagram and will now be described in detail.

In addition to the spiral series of bosses 90 the constantly rotating drum is provided at its left end with a circular series of bosses 114, one for each station, which coat with a roller 115 on a spring arm 116 associated with a lower switch contact 117 which when momentarily lifted by the passage of a boss 114 will make closure with a fixed contact 118. This operation will occur as the initiatory stage in the tuning shift from one station to the next and slightly in advance of the closure of the corresponding solenoid circuit by contact of the associated boss 90 with the switch closing roller 89.

The closing of the switch 117-118 when the circuit is set for automatic operation by the turning of the control switch 113 to the point A will close a circuit comprising switch contact 117, wire 119, switch 113, wire 120 to line wire 132 and, from line wire 122 through wires 121 and 123 to solenoid coil 124 and return wire 125 leading to switch contact 118. The energizing of the solenoid coil 124 lifts armature lever 126 which is pivoted in its center and causes its inner end to be engaged by pivoted latch 127. The opposite end of the

lever 126 is drawn down thereby closing a group of relay switch 128 which conditions the circuit to be finally closed by the slightly deferred closure of contacts 87-86 when actuated by the particular boss 90 of the spiral series which is special to the tuning of the incoming station.

The relay circuit which includes the switch 128 comprises the following constituents: wire 129, secondary 130 of transformer whose primary 131 is in circuit with line wires 122 and 132, header wire 133 which is in circuit relation with each of the several circuit assemblies one for each station comprised in the group, lead wire 134 to switch contacts 135-136, wire 137 leading to solenoid 77 and return wire 138 leading back to movable spring switch 87 which is closed by boss 90 special to the circuit assembly in question. The circuit is completed through wire 139, switch 113a, which is movable in unison with 113, and return wire 140 leading to the relay switch 128.

In preparation for reception from a newly attuned station it is necessary that the momentarily muted loud speaker be restored to service and that the appropriate light be flashed on and the circuits now to be described are provided to attain these results. The switch 135 is formed of a strip of spring metal, the free upper end of which is engaged by and cammed to circuit closing position by the lowering of the end of the associated thrust bar and which is connected with a spring switch member 141 which effects delayed energizing of an unlocking relay for releasing the latch 127 after a brief interval of time in a manner presently to be described.

The spring switch member 135 when moved makes circuit closing engagement with contact 142 in a light circuit including wire 143, bulb 99, header wire 144 to secondary 130 and thence through return header wire 133 and branch wire 134 to switch 135.

The unlatching of the pivoted armature 126 and opening of switch 128 which is necessary to restore the loud speaker to service and the means to effect this result will now be described. The branch wire 121 leading from line wire 122, leads to the last of a series of contacts 145 on the last of the spring switch arms 141 of the respective assemblies. The last contact 145 is normally in closed relation with the last contact 146 on a wire section 147 which carries the next contact 145 at its opposite end and so on throughout the remainder of the group thus maintaining a normally closed series arrangement from end to end.

When a spring switch member 141 is depressed in unison with the connected switch member 135 the circuit is broken at that particular point. The last contact 146 connects with a return wire 147 in circuit with condenser plates 148-149 connected with branch wire 121. The condenser plates 148-149 are in circuit with a vacuum tube 150 which in turn is in circuit with an unlocking relay coil 151 whose core when energized serves to momentarily draw up the tail end of the pivoted latch 127 thereby releasing the armature lever 126 which is spring pulled to break the switch contact 128, it being understood that in the diagram three only of the switches are shown but that the number will correspond to the number of group assemblies comprised in the entire series. The arrangement is such that when any one of the contact switches 145-146 is opened, and when a charge of approximately 3 microfarads builds up in the condensers an impulse will be discharged through the vacuum tube which momentarily energizes the unlocking relay and un-

locks the switch armature 126 after a very brief interval, sufficient, however, to maintain the loud speaker in muted condition during the shift from one station to the next. The circuit to the unlocking coil also includes a rectifier 152 connected with the line wires while the motor 53 is in circuit through wires 153-154 and switch 154¹ with the line wires.

The means provided for cutting out the automatic operation to permit button control will now be described. In order to set the machine for hand operation the switch 113 with its companion 113a is moved from the positions A indicating "automatic" to the positions M indicating "manual." Thereafter a selected button 98 special to the intended tuning is depressed which operates the connected double switch contacts 155-155a, which close in unison with contacts 156-156a. The switch contact 155 connects with header wire 157 common to all the assemblies of the series while the switch contact 155a connects with header wire 158. Wire 157 leads to the M side of switch 113, and wire 158 leads to the M side of switch 113a. Contacts 156 and 156a are both connected with an extension of wire 138 leading to the solenoid coil 77 and like connections are provided for each assembly throughout the series.

When the switches 113 and 113a are moved away from the A positions the automatic circuits actuated by the rotation of the drum 91 are cut out so that the successive closing of the switches 87-86 by the spiral series of bosses on the drum is ineffective to produce energizing of the solenoids 77 which latter during button control are selectively energized at the will of the operator and for any period desired. This cutting out of the automatic control occurs since the wire 120 which leads to switch contact 117 is opened by the shifting of the contact 113 to the M position while the circuit including contacts 86-87 is likewise opened.

The following circuit is established when a selected button is depressed and switch 155-156 is closed from contact 155 through wire 157 to M, through switch 113, wire 120, branch wire 121, wire 123, coil 124, wire 125, branch header wire 159, common to all the assemblies and through switch contact 156 to 155. The energizing of this circuit by hand control corresponds to the automatic closing of switch 117-118 by the circular series of bosses 114 on the rotating drum which are ineffective during hand operation. In the hand operation, however, as in the automatic operation it is desirable that the closing of contacts 155-156 should slightly precede the closing of contacts 115a-115a which energize the solenoids 77 so that the loud speaker will be muted at the beginning of the adjusting operations.

The closing of switch contacts 155a-156a energizes the solenoids 77 through the following circuit: contact 155a, wire 158 to M, switch 113a, wire 140, switch 128, previously closed through the preceding circuit, wire 129, secondary coil 130, wire 134, switch 135-136, wire 137, solenoid coil 77, wire 138 to contacts 156a-155a.

The energizing of solenoid 77 draws down the vertical armature bar 71 and lowers the thrust bar 29 which breaks contacts 135-136 and contacts 145-146 and closes contacts 135-142. This closes the light circuit and momentarily energizes unlocking coil 151, unlatching the switch lever 126 and opening switch 128 to break the grounding of the loud speaker and bring in reception from the selected station for as long a period as is desired by the operator and until

another button is depressed which releases the previously latched armature bar 71 by the lowering of another bar 71 and thus establishes the same set of operating conditions through another circuit assembly of the series. Thus under button control the operating sequence is in the main identical with that effected automatically save for the fact that the operating sequence and the periods of reception from the various stations are under the selective control of the operator.

The dropping of the armature bar either automatically or by button control will lower the associated thrust bar which will then be advanced by the shuttle bar until it is released therefrom by a notch in the associated trip bar, thus rocking the condenser shaft to the degree for which adjustment is made and simultaneously illuminating the signal light special to the station for which the condenser is attuned.

By thrusting in the push button 102¹ the clearing plate 31 will be actuated to release any armature bar which may be depressed, and by turning the rod 100, the spring 106 will be thrown out of tension so that in these circumstances the hand button 25 may be turned to any desired degree and the shaft 24, being relieved from spring tension, will maintain any adjustment which may be manually imparted to the condenser shaft.

It is believed that the operation of the device will be clearly understood from the foregoing description. The mechanism is one which may be employed with all or a portion only of the sending stations comprising the complete group by properly positioning the bosses on the timing drum so that the stations will be tuned in successively in any desired sequence and at the same time the duration of the periods of reception may be regulated by either equal intervals or variable intervals of any desired period. The speed of rotation of the timing drum being constant, the reception intervals can be accurately computed and the constant reciprocation of the shuttle bar insures the prompt actuation of any thrust bar which may be released to engage the shuttle bar.

This is insured by reason of the fact that the momentary energizing of one of the solenoids will result in the instant latching of the depressed armature bar which may remain latched during several subsequent reciprocations of the shuttle bar and until a second bar has been depressed to release the first. Furthermore, the fact that the shuttle bar in its advanced position may underlie the line of fingers 31 on the group of thrust bars at the instant when an armature bar is lowered, makes no difference in the operation of the device, since the finger of the released thrust bar even if momentarily arrested by contact with the top of the shuttle bar, will thereafter drop into position to bring its butt end into the line of movement of the shuttle bar as soon as the same is retracted so that on the next advancing movement the end of the finger will be contacted and the thrust bar will be carried forward to the extent permitted by the adjustment of the latch bar.

There is thus no necessity for maintaining a close timing relation between the positions occupied by the bosses on the timing drum and the starting points in the advance and recession of the shuttle bar, although a constant timing relation is maintained between the rotation of the timing drum and the cycles of movement of the

shuttle bar since both of these mechanisms are driven from a single source of power.

The general construction of the mechanism is one which permits the use of metal stampings to be largely employed, and the structure as a whole is one which may be easily and speedily and accurately assembled and which affords means for precise adjustment of the latch bars to secure close tuning to the wave frequency of a multiplicity of stations. Although the invention has been described with particularity it is not the intention, unless otherwise indicated in the claims, to limit the same to the embodiment before described since numerous modifications in structure may be made without departing from the principles of the invention.

I claim:

1. In radio tuning mechanism the combination of condenser plates and a movable mounting for the same, a group of selectively actuated transmission elements each adapted to be brought into operative engagement with the movable mounting, a constantly operating movement imparting element, adapted to engage singly with each of the transmission elements, releasing devices for normally holding the transmission elements out of engaging relation with the movement imparting element, timing devices and connections for successively in timed order actuating the releasing devices to permit engagement of a released transmission element by the movement imparting element, and individually adjustable elements for limiting the period of engagement of each transmission element to impart the degree of movement to the mounting required in tuning to the variable frequencies of each of a group of transmitting stations.

2. In radio tuning mechanism the combination of condenser plates and a rock shaft mounting for the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, timing devices and connections for successively in timed order actuating the releasing devices to permit engagement of a released transmission element by the shuttle bar, and individually adjustable elements for limiting the period of engagement of each transmission element to impart the degree of movement to the rock shaft required in tuning to the variable frequencies of each of a group of transmitting stations.

3. In radio tuning mechanism the combination of condenser plates and a movable mounting for the same, a group of selectively actuated transmission elements each adapted to be brought into operative engagement with the mounting, a constantly operating movement imparting element, adapted to engage singly with each of the transmission elements, releasing devices for normally holding the transmission elements out of engaging relation with the movement imparting element, timing devices and connections for successively and selectively actuating the releasing devices to permit engagement of a released transmission element by the movement imparting element, individually adjustable elements for limiting the period of engagement of each transmission element to impart the degree of movement to the mounting required in

tuning to the variable frequencies of each of a group of transmitting stations, means for disabling the operation of the timing devices, and individual manually operable devices for selectively operating the several releasing devices.

4. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, timing devices and connections for successively and selectively actuating the releasing devices to permit engagement of a released transmission element by the shuttle bar, individually adjustable elements for limiting the period of engagement of each transmission element to impart the degree of movement to the rock shaft required in tuning to the variable frequencies of each of a group of transmitting stations, means for disabling the operation of the timing devices and individual manually operable devices for selectively operating the several releasing devices.

5. In radio tuning mechanism the combination of condenser plates and a rock shaft mounting the same, a group of selectively actuated transmission elements each adapted to be brought into operative engagement with the rock shaft, a constantly operating movement imparting element, adapted to engage singly with each of the transmission elements, releasing devices for normally holding the transmission elements out of engaging relation with the movement imparting element, timing devices and connections for successively and selectively actuating the releasing devices to permit engagement of a released transmission element by the movement imparting element, latching means adapted to engage and hold each of the releasing devices in actuated position until the timed actuation of the next releasing device, and individually adjustable elements for limiting the period of engagement of each transmission element to impart the degree of movement to the rock shaft required in tuning to the variable frequencies of each of a group of transmitting stations.

6. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, timing devices and connections for successively and selectively actuating the releasing devices to permit engagement of a released transmission element by the shuttle bar, latching means adapted to engage and hold each of the releasing devices in actuated position until the timed actuation of the next releasing device, and individually adjustable elements for limiting the period of engagement of each transmission element to impart the degree of movement to the rock shaft required in tuning to the variable frequencies of each of a group of transmitting stations.

7. In radio tuning mechanism the combination of condenser plates and a rock shaft mounting the same, a group of selectively actuated trans-

mission elements each adapted to be brought into operative engagement with the rock shaft, a constantly operating movement imparting element adapted to engage singly with each of the transmission elements, releasing devices for normally holding the transmission elements out of engaging relation with the movement imparting element, timing devices and connections for successively and selectively actuating the releasing devices to permit engagement of a released transmission element by the movement imparting element, latching means adapted to engage and hold each of the releasing devices in actuated position until the timed actuation of the next releasing device, individually adjustable elements for limiting the period of engagement of each transmission element to impart the degree of movement to the rock shaft required in tuning to the variable frequencies of each of a group of transmitting stations, means for disabling the operation of the timing devices, and manual means for actuating the several releasing devices.

8. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, timing devices and connections for successively and selectively actuating the releasing devices to permit engagement of a released transmission element by the shuttle bar, latching means adapted to engage and hold each of the releasing devices in actuated position until the timed actuation of the next releasing device, individually adjustable elements for limiting the period of engagement of each transmission element to impart the degree of movement to the rock shaft required in tuning to the variable frequencies of each of the group of transmitting stations, means for disabling the operation of the timing devices, and individual manually operable devices for selectively operating the several releasing devices.

9. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, timing devices and connections for successively and selectively actuating the releasing devices to permit engagement of a released transmission element by the shuttle bar, a swinging universal latch plate positioned to be swung by each of the releasing devices when actuated and to hold the same latched against return until the timed actuation of the next releasing device, and individually adjustable elements for limiting the period of engagement of each transmission element to impart the degree of movement to the rock shaft required in tuning to the variable frequencies of each of a group of transmitting stations.

10. In radio tuning mechanism the combination of condenser plates and a rock shaft mounting the same, a group of selectively actuated transmission elements each adapted to be brought into operative engagement with the rock shaft,

a constantly reciprocating shuttle bar adapted to engage singly with each of the transmission elements, releasing devices for normally holding the transmission elements out of engaging relation with the shuttle bar, timing devices and connections for successively and selectively actuating the releasing devices to permit engagement of a released transmission element by the shuttle bar, a swinging universal latch plate positioned to be swung by each of the releasing devices when actuated and to hold the same latched against return until the timed actuation of the next releasing device, individually adjustable elements for limiting the period of engagement of each transmission element to impart the degree of movement to the rock shaft required in tuning to the variable frequencies of each of a group of transmitting stations, means for disabling the operation of the timing devices, and individual manually operable devices for selectively operating the several releasing devices.

11. In radio tuning mechanism the combination of condenser plates and a rock shaft mounting the same, a group of selectively actuated thrust bars each adapted to impart rotation in variable degree to the rock shaft, a shuttle bar and means for imparting constant lateral reciprocation thereto, a group of releasing devices adapted normally to hold the associated thrust bars out of engagement with the shuttle bar, timing device and connections for successively and selectively actuating the releasing devices to bring each released thrust bar into the path of movement of the shuttle bar, and individually adjustable elements, one for each thrust bar for limiting the period of engagement of the thrust bar, with the shuttle bar to that required in turning the rock shaft to the desired tuning requirements.

12. In radio tuning mechanism the combination of condenser plates and a rock shaft mounting the same, a group of selectively actuated thrust bars each adapted to impart rotation in variable degree to the rock shaft, a shuttle bar and means for imparting constant lateral reciprocation thereto, a group of releasing device adapted normally to hold the associated thrust bars out of engagement with the shuttle bar, timing devices and connections for successively and selectively actuating the releasing devices to bring each released thrust bar into the path of movement of the shuttle bar, and individually adjustable elements, one for each thrust bar, for limiting the period of engagement of the thrust bar with the shuttle bar to that required in turning the rock shaft to the desired tuning requirements, means for disabling the operation of the timing devices, and manual means for selectively operating the several releasing devices.

13. In radio tuning mechanism the combination of condenser plates and a rock shaft mounting the same, a group of selectively actuated thrust bars each adapted to impart rotation in variable degree to the rock shaft, a shuttle bar and means for imparting constant lateral reciprocation thereto, a group of releasing devices adapted normally to hold the associated thrust bars out of engagement with the shuttle bar, timing devices and connections for successively and selectively actuating the releasing devices to bring each released thrust bar into the path of movement of the shuttle bar, and a group of individually adjustable latch bars one underlying each thrust bar, each latch bar being configured to afford riding contact for the associated thrust

bar to hold the same in engagement with the shuttle bar during a period commensurate with the adjustment of the latch bar.

14. In radio tuning mechanism the combination of condenser plates and a rock shaft mounting the same, a group of selectively actuated thrust bars each adapted to impart rotation in variable degree to the rock shaft, a shuttle bar and means for imparting constant lateral reciprocation thereto, a group of releasing devices adapted normally to hold the associated thrust bars out of engagement with the shuttle bar, timing devices and connections for successively and selectively actuating the releasing devices to bring each released thrust bar into the path of movement of the shuttle bar, and a group of individually adjustable latch bars one underlying each thrust bar, each latch bar being configured to afford riding contact for the associated thrust bar to hold the same in engagement with the shuttle bar during a period commensurate with the adjustment of the latch bar, means for disabling the operation of the timing devices, and individual, manually operable devices for selectively operating the several releasing devices.

15. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar, for variably timing the periods of possible engagement of the individual thrust bars with the movement imparting element, a constantly operating timing device, circuit connections for each of the solenoid coils, and switches positioned to be operated selectively and successively by the timing device.

16. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar for variably timing the periods of possible engagement of the individual thrust bars with the movement imparting element, a constantly rotating timing drum provided on its periphery with variously positioned bosses one for each solenoid coil, circuit connections one for each solenoid coil, and switches one in each circuit positioned in the path of movement of an associated boss and adapted to be actuated thereby to energize the associated solenoid.

17. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar, for variably timing the periods of possible engagement of the individual thrust bars with the movement imparting element, a constantly operating timing device, circuit connections for each of the solenoid coils, switches positioned to be operated selectively and successively by the timing device, and a universal latch bar adapted to engage and latch each of the armature bars when actuated and hold the same latched until the actuation of the next armature bar.

18. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar, for variably timing the periods of possible engagement of the individual thrust bars with the movement imparting element, a constantly rotating timing drum provided on its periphery with variously positioned bosses, one for each solenoid coil, circuit connections one for each solenoid coil, switches one in each circuit positioned in the path of movement of an associated boss and adapted to be actuated thereby to energize the associated solenoid, and a universal latch bar adapted to engage and latch each of the armature bars when actuated and hold the same latched until the actuation of the next armature bar.

19. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar, for variably timing the periods of possible engagement of the individual thrust bars

with the movement imparting element, a constantly operating timing device, circuit connections for each of the solenoid coils, switches positioned to be operated in timed order and successively by the timing device, a universal latch bar adapted to engage and latch each of the armature bars when actuated and hold the same latched until the actuation of the next armature bar, disabling means for preventing the timed energizing of the solenoids, and individually manually operable switches and circuit connections for selectively energizing the respective solenoids.

20. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar, individually adjustable devices, one for each thrust bar, for variably timing the periods of possible engagement of the individual thrust bars with the movement imparting element, a constantly rotating timing drum provided on its periphery with variously positioned bosses one for each solenoid coil, circuit connections one for each solenoid coil, switches one in each circuit positioned in the path of movement of an associated boss and adapted to be actuated thereby, a universal latch bar adapted to engage and latch each of the armature bars when actuated and hold the same latched until the actuation of the next armature bar, disabling means for preventing the timed energizing of the solenoids, individually manually operable switches and circuit connections for selectively energizing the respective solenoids, and means for disabling said circuit connections to permit direct manual adjustment of the rock shaft.

21. In radio tuning mechanism the combination of condenser plates and a movable mounting for the same, a group of selectively actuated transmission elements each adapted to be brought into operative engagement with the movable mounting, a constantly operating movement imparting element, adapted to engage singly with each of the transmission elements, releasing devices for normally holding the transmission elements out of engaging relation with the movement imparting element, means for actuating the releasing devices to permit engagement of a released transmission element by the movement imparting element, and individually adjustable elements for limiting the period of engagement of each transmission element to impart the degree of movement to the mounting required in tuning to the variable frequencies of each of a group of transmitting stations.

22. In radio tuning mechanism the combination of condenser plates and a movable mounting for the same, a group of selectively actuated transmission elements each adapted to be brought into operative engagement with the movable mounting, a constantly operating movement imparting element, adapted to engage singly with each of the transmission elements,

releasing devices for normally holding the transmission elements out of engaging relation with the movement imparting element, means for actuating the releasing devices to permit engagement of a released transmission element by the movement imparting element, and individually adjustable elements for limiting the period of engagement of each transmission element to impart the degree of movement to the mounting required in tuning to the variable frequencies of each of a group of transmitting stations, and automatic means for cutting out the tuning effect during periods of adjustment and restoring the effect thereafter.

23. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, means for actuating the releasing devices to permit engagement of a released transmission element by the shuttle bar, and individually adjustable elements for limiting the period of engagement of each transmission element to impart the degree of movement to the rock shaft required in tuning to the variable frequencies of each of a group of transmitting stations.

24. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, means for actuating the releasing devices to permit engagement of a released transmission element by the shuttle bar, and individually adjustable elements for limiting the period of engagement of each transmission element to impart the degree of movement to the rock shaft required in tuning to the variable frequencies of each of a group of transmitting stations, and automatic means for cutting out the tuning effect during periods of adjustment and restoring the effect thereafter.

25. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, means for actuating the releasing devices to permit engagement of a released transmission element by the shuttle bar, latching means adapted to engage and hold each of the releasing devices in actuated position until the timed actuation of the next releasing device, and individually adjustable elements for limiting the period of engagement of each transmission element to impart the degree of movement to the rock shaft required in tuning to the variable frequencies of each of a group of transmitting stations.

26. In radio tuning mechanism the combination of condenser plates and a rock shaft mount-

ing the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, means for actuating the releasing devices to permit engagement of a released transmission element by the shuttle bar, latching means adapted to engage and hold each of the releasing devices in actuated position until the timed actuation of the next releasing device, and individually adjustable elements for limiting the period of engagement of each transmission element to impart the degree of movement to the rock shaft required in tuning to the variable frequencies of each of a group of transmitting stations, and automatic means for cutting out the tuning effect during periods of adjustment and restoring the effect thereafter.

27. In radio tuning mechanism the combination of condenser plates and a rock shaft mounting the same, a group of selectively actuated transmission elements each adapted to be brought into operative engagement with the rock shaft, a constantly reciprocating shuttle bar adapted to engage singly with each of the transmission elements, releasing devices for normally holding the transmission elements out of engaging relation with the shuttle bar, means for actuating the releasing devices to permit engagement of a released transmission element by the shuttle bar, a swinging universal latch plate positioned to be swung by each of the releasing devices when actuated and to hold the same latched against return until the timed actuation of the next releasing device, and individually adjustable elements for limiting the period of engagement of each transmission element to impart the degree of movement to the rock shaft required in tuning to the variable frequencies of each of a group of transmitting stations.

28. In radio tuning mechanism the combination of condenser plates and a rock shaft mounting the same, a group of selectively actuated thrust bars each adapted to impart rotation in variable degree to the rock shaft, a shuttle bar and means for imparting constant lateral reciprocation thereto, a group of releasing devices adapted normally to hold the associated thrust bars out of engagement with the shuttle bar, means for actuating the releasing devices to bring each released thrust bar into the path of movement of the shuttle bar, and a group of individually adjustable latch bars one underlying each thrust bar, each latch bar being configured to afford riding contact for the associated thrust bar to hold the same in engagement with the shuttle bar during a period commensurate with the adjustment of the latch bar.

29. In radio tuning mechanism the combination of condenser plates and a rock shaft mounting the same, a group of selectively actuated thrust bars adapted to impart rotation individually in variable degree to the rock shaft, a constantly operating movement imparting element adapted to engage singly with each of the thrust bars, releasing armature bars, one for each thrust bar, adapted normally to hold the thrust bars out of engagement with the movement imparting element and adapted when actuated to bring the associated thrust bar into engagement therewith, a solenoid coil surrounding each armature bar and adapted when energized to draw the same

into position to release the associated thrust bar; individually adjustable devices, one for each thrust bar, for variably timing the periods of possible engagement of the individual thrust bars with the movement imparting element, a constantly operating timing device, circuit connections for each of the solenoid coils, switches positioned to be operated in timed order and successively by the timing device, a universal latch bar adapted to engage and latch each of the armature bars when actuated and hold the same latched until the actuation of the next armature bar, disabling means for preventing the timed energizing of the solenoids, and individually manually operable switches and circuit connections for selectively energizing the respective solenoids, said switches and connections including means for cutting out the circuit connections operated by the timing device and including means for timing the energizing of solenoids at the will of the operator.

30. In radio tuning mechanism the combination of condenser plates and a rock shaft mounting the same; a group of selectively actuated thrust bars adapted to impart rotation individually in variable degree to the rock shaft, a constantly operating movement imparting element adapted to engage singly with each of the thrust bars, releasing armature bars, one for each thrust

bar, adapted normally to hold the thrust bars out of engagement with the movement imparting element and adapted when actuated to bring the associated thrust bar into engagement therewith, a solenoid coil surrounding each armature bar and adapted when energized to draw the same into position to release the associated thrust bar; individually adjustable devices, one for each thrust bar, for variably timing the periods of possible engagement of the individual thrust bars with the movement imparting element, a constantly operating timing device, circuit connections for each of the solenoid coils, switches positioned to be operated in timed order and successively by the timing device, a universal latch bar adapted to engage and latch each of the armature bars when actuated and hold the same latched until the actuation of the next armature bar, disabling means for preventing the timed energizing of the solenoids, and individually manually operable switches and circuit connections for selectively energizing the respective solenoids, and circuit means and electrically operated devices for cutting out the tuning effect during periods of adjustment whether effected automatically or manually and adapted to automatically restore said tuning effect after a timed interval of readjustment.

ALBERT S. WELLS.
